UNITED STATES PATENT OFFICE

2,206,761

MACHINE AND METHOD FOR PACKAGE CLOSURE

Robert Morris Bergstein, Cincinnati, Ohio

Application October 17, 1938, Serial No. 235,315

18 Claims.

(Cl. 93—6)

In my United States Patent No. 2,095,910, issued October 12, 1937, and No. 2,114,621, issued April 19, 1938, I have disclosed machines and methods for making knock-down containers comprising an outer carton with inner liner secured therein, which liner may be open at both ends, or closed at one end, as desired. It is desirable in many instances to have the outer carton made of board that has been treated to be waterproof, as for example by paraffin or the like, and in such cases it is difficult, if not impossible, to satisfactorily seal with adhesive the carton flaps to effect the final carton closure, due to the impermeable nature of the surface. Accordingly in many cases the carton flaps have been secured in closing position by locking rather than sealing, the locking usually taking the form of a slot in one flap and a corresponding tongue in the other opposite flap, which are engaged in interlocking position. This locking has customarily been done by hand, and I have discovered means and method for carrying out this locking operation efficiently by machine, and this is one of the objects of my invention.

In my United States Patents Nos. 2,114,622, 2,114,623 and 2,114,624, I disclosed means and method for sealing the mouths of liners within cartons. By my invention as herein disclosed, I now accomplish the sealing of the liner, and the interlocking of the carton flaps, as part of a series of continuous operations, providing for the complete closure of the package, efficiently and without hand manipulation.

By my invention, a single machine may also be provided which provides a closure for both ends of the package, that is which receives a container comprising an outer carton having locking flaps, and an inner liner secured therein, with both ends of said liner open, which accomplishes the operation of sealing an end of the liner, interlocking the flaps thereabout (when the container may then be inverted and filled with the contents), thereafter the same machine will convey the filled container closing the remaining open end of the liner, and finally locking the flaps about the final closed liner end. Among other features in connection with this machine I disclose means whereby a series of cages may be used to retain the containers during their course of travel, said cages having cut-away portions, and a stationary guide-bar, whereby the same cages may be used to convey both the empty or filled container, compensating for the difference in height, which is a still further object of my invention.

These and other objects of my invention will become apparent as the description proceeds.

Reference is now made to the drawings wherein:

Fig. 1 is a side elevation of my machine, having parts broken away and certain parts in section, with various supporting elements for the several guide bars omitted, so as to permit a clear illustration of the points involved in my invention.

Fig. 2 is a top plan view of the mechanism seen in Fig. 1, having a portion thereof broken away.

Fig. 3 is a sectional view taken along line 3—3 of Fig. 1.

Fig. 4 is a perspective showing one of the cages and associated members I employ to carry the cartons through my machine.

Fig. 5 is a fragmentary side elevation illustrating a latch for retaining the front end flap of the carton in a downward position during certain operations and means for releasing the latch when desired.

Fig. 6 is a perspective of the latch member.

Fig. 7 is a section taken along line 7—7 of Fig. 2, showing means for spreading the carton mouth and showing the heat sealing members in open position.

Fig. 8 is a fragmentary front elevation of the spreading means seen in Fig. 7, showing in broken lines the extended position of the fingers within the carton mouth.

Fig. 9 is a sectional view taken along the line 9—9 of Fig. 2, illustrating means for actuating the sealing members.

Fig. 10 is a view similar to Fig. 9 but showing the sealing members in closed position.

Fig. 11 is a perspective showing certain guide bars which serve to turn down the sealed mouth of the carton liner.

Fig. 12 is a perspective showing a preferred arrangement of members for closing and interlocking the tongued and slotted side flaps of the carton.

Fig. 13 is a section taken along the line 13—13 of Fig. 2 showing an ejector and means for operating same in timed relation to the conveyor movement.

Fig. 14 is a diagrammatic plan view illustrating a scheme for remote filling of the cartons.

Fig. 15 is a perspective showing a modified carton closure and an alternative means for interlocking same.

Fig. 16 is a perspective of a carton in knock-down condition, and

Fig. 17 is a perspective of the carton squared up in preparation for loading the machine.

As shown in Figs. 1 and 2, a suitable frame 1 supports a table-like surface 2, having formed 5 therein a conveyor track 3. The conveyor chain 4 is driven by a right hand sprocket 5 fixed to a shaft 6, and runs over a sprocket 7 which is fixed to a shaft 8. Thus any movement of the shaft 6 results in similar movement of shaft 8.

10 Referring to Fig. 3 the conveyor chain is driven intermittently by action of a four-stop Geneva mechanism, the driven wheel 9 of which is fixed to the shaft 6. The driving pin 10 and locking member 11 of the Geneva mechanism are here 15 fixed to a large gear 12, said gear being in turn driven by a motor 13 through a belt 14, a pulley 15, a shaft 16 and a worm 17. The intermittent mechanism is enclosed in a suitable casing 18 having journaled bearings as required. Fixed to 20 the large gear 12 is a vertical shaft 19 which extends upward through the table-like surface 2, and is provided at its upper end with a miter gear 20, meshing with a like gear 21, fixed on the longitudinal shaft 22. The shaft 22 is journaled 25 in bearing brackets 23 and 24 and has affixed various cams and gears, the purpose of which will be later explained. From the foregoing it will be apparent that the shaft 22 is driven in timed relation with the conveyor movement and that 30 for each movement of the conveyor the shaft 22 will make one complete revolution.

The conveyor chain is provided with a series of equally spaced plates 25, which, referring to Fig. 4, are provided with a pair of upstanding 35 members 26, 26. The members 26 are held to the conveyor plates by screws 26a passing through slots 26b which permit re-setting of the members 26 to accommodate various widths of cartons. The members 26 have cut-out portions 40 26c, the purpose of which will be later explained.

Referring to Fig. 16, I have shown in knock-down condition one type of carton for which my machine is particularly adapted. The carton body 27 here shown may be formed of any desired 45 paper board or cardboard material. One of the principal advantages of my invention, however, is the ability of my mechanism to form an effective closure in a carton, the outer body material of which has been impregnated with par- 50 affin or the like, rendering satisfactory sealing of the end flaps difficult by use of adhesive or the like, as in present practice. The carton here shown has an inner heat sealable liner 28 secured to the inner-side walls, this liner, for pur- 55 pose of sealing, being of sufficient length to extend beyond the carton walls. Articulated by score lines or fold lines 29 at each end of the body are a set of closure flaps generally indicated at 30 and 30a. As better seen in Fig. 12 60 the side flap 31 is formed with a tongue 31a which is adapted to engage within a slot or cut 32 of side flap 33. The slot or cut 32 has adjoining angular cuts 32a which are in turn ad- 65 joined by a score or fold line 32b; thus a weak- 70 ened portion which is readily bendable is formed. Due to the direction of travel as indicated by the arrows in Fig. 12, I shall refer to the flap 34 as the leading or front end flap and the flap 35 shall be referred to as the trailing or rear end 75 flap, the designation of these flaps being an arbitrary matter depending on the direction of travel.

As previously described the conveyor is driven intermittently or in steps, the distance of travel during movement being equal to the center to

center distance of consecutive conveyor plates. Thus a series of stops or stations are established which are advantageous in performing certain operations. As shown in the drawings the conveyor is in the position it assumes during a period of rest.

Before filling the cartons must be set up with the ultimate bottom seal of the liner completed. The extending portion of the sealed liner must be folded within the box and the adjacent side 10 flaps turned in and interlocked. The mechanisms for accomplishing these results are incorporated in my machine, the required operations occurring while the carton travels between the stations indicated in the drawings at A and E. 15

After the carton has thus been erected or set up, it is ready to receive the contents, which contents may be inserted therein by any means or apparatus best suited to handle that particular type of contents or material in consideration. In 20 the machine illustrated I have shown at 36 a conventional filling head, and as seen in Fig. 2, the filling of the carton may occur at station F, or if a slower rate of filling is required, part of the contents may be inserted at station F and the 25 balance at station G; or the filling may be a continuous operation commencing at station F and continuing while the carton travels to and rests at station G.

After filling it will be required to seal the open 30 mouth of the liner, fold same within the box and close and interlock the end flaps. These operations are identical with those required for setting up the carton as previously described, and take place while the carton travels between stations G and K. The sealing and closing mechanisms here employed are an exact duplication 35 of the mechanisms interposed between stations A and E.

In the operation of the machine the operator 40 picks up the flat carton as seen in Fig. 16, squares it manually to the open position seen in Fig. 17, and places it between the upstanding members 26 as seen at A in Fig. 1. Referring to Fig. 5, the leading or front end flap 34 is bent downward along its line of articulation against the angular member 38 until it engages and is held under the latch 37. The trailing or rear end flap 35 is bent downwardly along its line of articulation against the angular member 39. This 45 bending of the flaps 34 and 35 against the members 38 and 39 provides proper vertical placement of the carton for cooperation with the sealing and closing mechanisms. As shown the flap 35 after being bent downward will tend to re- 50 turn to its original position, likewise the flap 34 will spring upward tending to return to its original position when the latch 37 is released. The latch 37 is released when the sidewise extending portion 31a is depressed by striking the station- 55 ary cam bar 37b. To provide for various size cartons the members 38 and 39 have adjustment slots 40 through which screws 41 extend, said screws being threaded into the members 26. For proper transverse placement the carton abuts an 60 inner side guide rail 42, which rail is adjustably mounted to accommodate other size cartons.

When the conveyor starts to move the carton at station A, carried therewith, will first be engaged by an outer side guide rail 43 which is 65 also adjustably mounted and extends along the machine to a position at station E where the carton is to be temporarily ejected from the machine. It will be observed that the members 26 mounted on each conveyor plate, cooperating 70 75

with the guide rails 42 and 43, effect a series of traveling cages, to guide the cartons in required alignment through the machine. It is also to be noted that the arrangement shown is capable of ready adjustment to convey other size cartons.

As the carton travels onward the flaps 31, 35 and 33 are engaged and turned downward by curved bars 44 and 45, which bars have straight 10 extended portions 46 serving to retain the said flaps in the downward position as required during sealing of the inner liner.

The movement of the conveyor pauses when the carton reaches the position or station indicated 15 at B, and it is here that sealing of the inner liner takes place. The sealing mechanism here employed is similar to that described and claimed in my patents previously referred to. Referring to Figs. 7 and 8, a pair of fingers 47 and 48 are 20 slidably mounted on studs 47a and 48a. The fingers have curved slots 47b and 48b and are perforated at their upper end to receive an operating bar 49. The bar 49 is pivoted at 49a in an upstanding bracket and has an extended portion 49b with 25 cam roller 49c engaged by the cam 49d on shaft 22. The member 49 is urged to the position shown by the spring 49c. When the member 49 descends due to action of the cam 49d, the fingers 47 and 48 riding over the studs will descend and be expanded within the open mouth of the carton liner as seen in broken lines. The liner is thus spread and partially flattened as seen in Fig. 9, where the spreader fingers have been omitted from the drawing and the heat sealing elements are shown 30 in open position. The sealing elements 50 and 51 are of the electrical heated type being mounted on arms 52 and 53 affixed to the shafts 54 and 55, which shafts are in turn journaled in brackets 56 and have fixed at their outer ends gears 57 and 40 58. The gear 58 has a stud 58a connected with a cam follower 59 by a link 59a. The assembly is urged to the position shown by the tension spring 60. As can be readily determined by inspection of the drawings, the action of the cam 61 (fixed 45 on the shaft 22) will cause the heating elements to be carried to the closed position seen in Fig. 10. The element 50 is provided with a tongue or bead 50a and the opposite element 51 is provided with a groove 51a. As the tongue and groove elements 50 contact the liner, so that the tongue enters at least partially into the groove causing the liner material to become curved, heat being present causes the opposite inner faces of the liner mouth to become fused. Attached beneath the heating 55 elements are a pair of sweepers 50b and 51b. The object of these sweepers is to evacuate the air out of the open mouth of the bag and partially from the interior or below the upper edge of the carton. These sweepers are so mounted that they 60 precede the contact of the heating elements so that the air is expelled before the heat seal is made. Referring to Fig. 11, the appearance of the flattened and sealed liner mouth (after the spreader fingers and sealing elements have re- 65 ceded) is shown at X.

After the sealing operation as just described, the conveyor again starts to move and the up-standing sealed liner X is engaged between a pair of curved guides 62 and 63 (best seen in Fig. 11) 70 which as the carton moves along serve to turn down the sealed end of the liner. The extended portion 63a of guide 63 retains the liner in downward position while the front end flap 34 is bent inward and down by action of a bar 64 (see Figs. 1 and 12), the flap 34 having just previously been

released from the latch 37 by action of the cam bar 31b. In turning or folding over the flap 34 the overlying portion of the liner will be carried therewith and folded inwardly beneath the flap. The hold-down bars 46 terminate just previous to 5 this point and release the flaps 31, 33 and 35 allowing them to spring upward. The conveyor then comes to rest at station C.

Just as the carton is about to leave station C the trailing or rear end flap 35 and the overlying 10 portion of the liner mouth are turned inward and down by the rotating element 65 (Figs. 1 and 2), further movement of the carton causes the flap to be engaged under the bar 64 which retains it in downward position while the remaining flaps 31 15 and 33 are folded and interlocked as will presently be explained. The rotating element 65 is mounted on shaft 66 journaled in bearing bracket 67, and is driven in timed relation with the conveyor by a pair of spiral gears 68, the driver of 20 which is fixed on shaft 22.

Referring to Fig. 12 the carton at C' is shown just as the folding and interlocking of flaps 31 and 33 is about to commence. As the carton moves forward a curved bar 69 engages the ultimate upper side of the slotted flap 33. The hold down bar 64 is bent sidewise as at 64a so as to bring its outer edge into alignment with the line of articulation of flap 33 and has an extending enlarged cross sectional portion 64b. The curvature 30 of bar 69 is such that the flap 33 will be turned inward and down against the carton body with the enlarged portion 64b of bar 64 underlying the flap. This action tends to open the slot 32 and the position of the flap at this point is seen at D'. 35 It is to be noted that the extended underside 69a of the bar 69 retains or holds down the flap 33 in its folded position and that an enlarged portion or hump 69b of the bar 69 coextensive with the underside 69a underlies the tongued flap 31, which 40 flap is turned over by a curved bar 70. Referring to the carton at C' the curved bar 70 engages the ultimate upper side of flap 31 and in turning the flap about the enlarged portion 69b the effective length of the tongue is reduced, that is, the distance of a straight line or chord between the line 45 of articulation 31b and the edge of the tongue 31c is shortened, due to the fact that the flap 31 is in curved formation. The enlarged portion 69b gradually tapers off to the point of termination 50 69c, so that as the carton progresses the effective length of the tongue is increased. As seen on the carton at D' the edge of the tongue 31c is in a position favorable for entry into the slot 32. The extended portion 70a of the bar 70 is arranged to 55 press downward on the flap so that as the carton moves forward and the effective length of the tongue 31a is increased it will enter the slot 32 due to pressure of the overhead guide 70a. As the carton passes the terminal points 64c and 69c 60 of the enlarged members the portion 70b of the bar 70 will urge the tongued flap into completely interlocked position. The flaps are then in their normal plane and the ultimate bottom of the container completely formed. After passing the terminus 70b of the overhead guide the carton will have arrived at station E. From the foregoing it will be observed that the bar 70 serves as an overhead guide for the tongued side flap; the bar 69 serves the dual purpose of an overhead guide 70 for the slotted flap and an underneath guide for the tongued flap; and the bar 64 functions as an underneath guide for the slotted flap while retaining the end flaps 34 and 35 in their folded position.

At station E the carton is immediately ejected from the machine by an ejector arm 71, which arm after ejecting the carton immediately recedes to permit re-insertion of the carton in its upright position for filling. The ejector arm 71 is fixed on the shaft 11a journaled in bearing brackets 12 and 12a. Fixed to shaft 11a the lever arm 71b has pivoted thereto a link 73, which link is actuated by a cam 14 on the shaft 22. After operation of the device, as indicated by the broken lines in Fig. 13, the mechanism is returned to its inoperative position by tension of the spring 75.

In replacing the carton, in its upright position, at station E, the operator will follow the same procedure as outlined in the description previously given in reference to station A, that is, the leading end flap 34 will be engaged under the latch 37 and the carton will be located vertically by bending of the flaps 34 and 35 against the gauge members 38 and 39. The carton also abuts an inner guide rail 42a. It is to be noted that the flaps articulated to this upper end of the carton and the arrangement of the extending inner liner therewith, is merely a duplication of those members as already described in regard to forming the bottom of the container, and have been given like reference numerals in the drawings.

As the conveyor carries the carton away from station E, a side guide bar 43a serves to hold the carton in proper alignment, and curved bars 80 and 81 turn down and outward the flaps 31, 33 and 35. The bar 43 extends about the machine to a point where the cartons will be finally ejected at station K. Also as the carton leaves station E, it rides onto an underneath bar 79 which will support the carton and the weight of the contents therein for proper cooperation with the final sealing and closing mechanism encountered after filling. The bar 79 is provided with vertical adjustment to accommodate other size cartons and extends about the machine to the station K where as before mentioned, the cartons are finally ejected from the machine. The bar 79 is permitted to enter beneath the cartons by the cut away portions 26c of the upright members 26 best seen in Fig. 4.

Fixed to rotate with shaft 8 the filling head 36 has a plurality of rotating spouts 36a timed to travel with the cartons in their movement between stations E and G. The filling head has a stationary member 36b in which the required valves or ports for controlling flow of material through the spouts and into the containers may be incorporated. The member 36b is restrained from rotation by the stud 36d which abuts the fixed upright bar 36e and a supply line is indicated at 36c. It will be understood that the filling mechanism here shown is of exemplary construction and I am not to be limited to the particular arrangement or type of filling mechanism here shown.

As previously described and explained, a carton passing beneath the filling head and arriving at station G will have the contents therein and will be ready for the final sealing and closing operations. Further movement of the conveyor carries the carton to station H where the open mouth of the inner liner is spread and sealed by mechanism similar to that described at station B. The spreader fingers at station H are actuated by a cam 81 fixed on the shaft 22, and the sealing members are actuated by a cam 83 also fixed on the shaft 22. At station I the leading or front end flap 34 is turned down against the carton body by the bar 64x, and the trailing

end flap 35 is turned down by the rotating element 65x driven from the shaft 22 through a spiral gearing 84. Interposed between stations I and K are folding and interlocking bars 64x, 69x and 70x, which function to close and interlock the remaining side flaps. At station K the ejector arm 71x expels the completely filled and sealed container from the machine. The ejector 71x is actuated by a cam 85 on the shaft 22.

No particular function or operation will occur at the stations marked D and J, as the interlocking of the side flaps will preferably require a greater distance of travel than is afforded between consecutive stations in the arrangement shown.

In conjunction with the interlocking of the side flaps and to complete the folding thereof I may employ an extra pair of guides or pressure members (10c), longitudinally disposed, to act upon the two opposite edges of the carton by pressing along the longitudinal edges of the folds, thus assuring more dependable interlocking, as well as providing a more dependable flattened condition for the cartons to stand in upright position for filling or other purposes.

In Fig. 4 I have shown a simple but effective means to provide adjustable supports for the various guide rails. Here the bracket 95 is fixed to the machine frame and has a vertical extending rod 96 on which a block 97 is held by set screw 98. The block is bored as at 99 to receive a rod 100, said rod being clamped within the block by set screw 101. The inner end of the rod 100 is fixed to the guide member in any convenient manner as at 102. With this arrangement any desired position of the guide members may be obtained.

In some cases it will be desired to eliminate the filling head 36 and receive the cartons ejected at station E upon a conveyor as shown at 76 in Fig. 14. Here the cartons ejected onto conveyor 76 are transferred to a secondary conveyor 16a upon which conveyor they may be filled by the machine 11. For hand packing of the cartons the machine 11 will be replaced by a packing table. After filling, the cartons are transferred to another conveyor 16b, which carries them to a convenient position near the station G where the filled carton is again loaded onto the machine for sealing of the open liner mouth and interlocking of the end flaps by mechanism interposed between stations G and K. At K the filled and sealed carton is again ejected from the machine and may be received upon a conveyor 78 for final disposition as required.

In Fig. 15 I have illustrated an alternate interlocking device. As shown this consists of a timed overhead cam 93, which is synchronized with the course of travel of the container, and as the container passes beneath this cam with the flaps 90 and 91 previously folded to the normal interlocking plane, the cam becomes operative and the nose bears down upon the folded flaps over the slotted and tongued portion, serving to depress this portion. The effect of this depression is to lower the tongued and slotted flaps beneath the normal interlocking plane, thereby bringing the edge of the tongue 91b into position adjoining the slot 90a, so that when in the further course of motion of the container the cam continues to revolve and thereby the pressure on the flaps is released, and the flaps will resume their normal plane, in interlocked position. With this arrangement the flaps may be interlocked while the carton is stationary, if desired.

It can be seen that this alternate interlocking

device as described is less desirable than my preferred device since in order to foreshorten the tongued flap or the slotted flap, or both, it bends said flap or flaps from their normal interlocking plane, this foreshortening serving the purpose of bringing the edge of the tongue into operative position adjacent the slot so that when the flaps are released back into their normal position or plane, they are in interlocked engagement. In the case of my preferred method as described, the foreshortening is accomplished as explained by curving or arching the flap or flaps, which serves to shorten the transverse distance between the fold line of the flap and the edge of the tongue or slot, while in my alternate method as described above the flaps are depressed below their normal plane, also effecting a shortening of the transverse distance between the fold line of the flaps and the edge of the tongue or slot. This latter method will be interfered with by the contents of a package after filling and will push down on the liner when empty.

It is obvious that the location and nature of the slot, also of the tongue may be varied if desired without departing from the spirit of this invention, and if desired, due to the size or shape of the flaps, a plurality of tongues and slots may be utilized, and are adaptable to my same interlocking process. It is obvious that variations may be made in the shape and location of the guides if desired. For example, if a complete cut-away slot is utilized, it may not be necessary to have an underneath slotted side flap guide, since the operation may be performed successfully through the use of the overhead slotted side flap guide, and the underneath tongued side flap guide and overhead tongued side flap guide. While I prefer to have these guides stationary and move the carton through them, it would also be possible to have the carton at rest or moving in an opposite direction, and use movable guides, and all such variations are contemplated within the scope of my invention, so long as the basic interlocking principles as described herein, are utilized.

Due to the arrangement illustrated and described using cages with cut-away areas and interposing a stationary guide in the said areas, it can be seen that I have provided extremely simple and effective means of providing a continuous conveyance for packaging of varying overall heights. That is, if a carton with an inner liner having both ends open is used, so that a seal at both ends is necessary, whereby the carton when initially introduced into the machine has the flaps at both ends extending, it is obvious that this height is greater by the length of the flaps, than the same carton after one end has been closed, and the flaps folded to their normal interlocking plane. Without this feature, it would be necessary to either have cages of varying height which would reduce the machine's production, or else to make variations in the height of the locking and sealing members, which would introduce extra mechanical difficulties. I may also adapt this same principle to side adjustments instead of a vertical adjustment, if desired, by using cutouts in the sides of the cages, and a stationary guide bar, whereby the carton can be inserted just up to the side guide bar, thereby permitting ready variation in the width of the carton without the need of complicated adjustments, or changing the cages themselves.

It will be apparent that my process is adaptable to automatic interlocking of ordinary un-

lined cartons if desired. My automatic interlocking principle is also adapted, as described, to form parts of a continuous operation wherein lined cartons are used, the device effecting the heat-sealing and folding of one end of a liner within the carton, thereafter interlocking the flaps at said end of the carton, and, as illustrated, by further employment of the same principle the device can continue after the container has been filled, to seal the remaining end of the liner, folding it into position thereafter, and thereafter making the final interlocking closure of remaining end, completing the package. It is obvious, however, that my invention could be separated into two units, if desired, one for accomplishing the sealing and folding of a liner and interlocking the flaps at one end of the carton, and the other unit to produce the same result on the remaining end of the container, after having been filled. The particular arrangement of the device or the devices in this regard is optional, and all such variations are contemplated within the scope of my invention.

Having thus described my invention, what I claim as new and desire to secure by Letters Patent, is:

1. A device for interlocking a pair of opposite carton flaps, one of which includes a projecting tongue and the other of which includes a slotted or weakened portion, which comprises folding means to fold said flaps toward their normal interlocking plane by overhead guides, and underneath guides located to engage under said flaps so as to bow the same and bring the edge of said tongue adjacent to said slotted portion, and pressing means to press on said tongued flap, thereby releasing said tongue into engaged position with said slotted or weakened portion all of aforesaid guides and means being stationary relative to each other, and means for causing relative movement between the carton and the underneath guides as the pressing means are applied.

2. In a machine for interlocking a pair of opposite flaps articulated to a carton body, one of which flaps has a tongue and the other of which has a corresponding slot, means for folding and deflecting said flaps to bring the edge of said tongue adjacent to said slot, and means for releasing said flaps to their normal interlocking plane in interlocked position, said means being stationary relative to each other.

3. In a machine for closing the flaps articulated to an end of a carton body, one opposite pair of which flaps include a tongued flap and the other a corresponding slot, means for conveying said carton in direction of motion parallel to the fold lines of said last mentioned pair of flaps, means for folding in the other pair of opposite flaps, means for retaining said flaps in folded position, and means during further travel of carton to bring said tongued flap and slotted flap between curved overhead, and underneath guides which deflect said flaps thereby shortening transverse distance between edge of tongue and line of articulation to bring the edge of said tongue adjacent to the slot, said underneath guides being tapered, whereby upon still further travel of the carton, said flaps will assume normal interlocking plane, in interlocked position, after having passed beyond said guides.

4. In a machine for closing the flaps articulated to an end of a carton body, one opposite pair of which flaps include a tongued flap and the other a corresponding slot, means for con-

veying said carton in direction of motion parallel to the fold lines of said last mentioned pair of flaps, means for folding in the other pair of opposite flaps, means for retaining said flaps in folded position, and means during further travel of carton to bring said tongued flap and slotted flap between curved overhead, and underneath guides which deflect said flaps thereby shortening transverse distance between edge of tongue and line of articulation to bring the edge of said tongue adjacent to the slot, said underneath guides being tapered, whereby upon still further travel of the carton, said flaps will assume normal interlocking plane, in interlocked position, after having passed beyond said guides, and means to enforce the resumption of said plane of said flaps.

5. In a machine for interlocking an opposite pair of flaps articulated to an erect carton, one of which flaps has at least one tab thereon, and the other of which flap has at least one slot or weakened portion corresponding thereto, means including guide members, comprising an underneath guide for slotted flap, an overhead guide 20 for the tongued flap, and one common guide successively serving as an overhead guide for said slotted flap and underneath guide for said tongued flap, for the purpose described.

6. In a machine for interlocking an opposite pair of flaps articulated to an erect carton, one of which flaps has at least one tab thereon, and the other of which flap has at least one slot or weakened portion corresponding thereto, means including guide members, comprising an underneath guide for slotted flap, an overhead guide 30 for the tongued flap, and one common guide successively serving as an overhead guide for said slotted flap and underneath guide for said tongued flap, for the purpose described, the last noted guide progressively tapered and ending before the overhead guide for the tongued flap ends, whereby the continued pressure of said overhead tongued flap guide, serves to press the tongue into engagement with corresponding flap 40 by causing the tongue to enter the slot, and means for moving the carton with respect to the guides.

7. In a machine for interlocking a pair of opposite flaps projecting from an erect carton, one of which flaps has a tab thereon, and the other of which flap has at least one corresponding slotted portion thereon, means to convey said carton in the direction of motion parallel to the fold lines of said flaps, stationary guide members located in the path of travel of said flaps and having a contour and located so as to cause successive arching of said slotted flap to bring said slot into open position, and arching said tabbed flap to bring the edge of said tab adjacent to said open slot, for the purpose described.

8. In a machine for interlocking a pair of opposite flaps projecting from an erect carton, one of which flaps has a tab thereon, and the other of which flap has at least one corresponding slotted portion thereon, means to convey said carton in the direction of motion parallel to the fold lines of said flaps, guide members located in the path of travel of said flaps and having a contour and located so as to cause successive arching of said slotted flap to bring said slot into open position, and arching said tabbed flap to bring the edge of said tab adjacent to said open slot, for the purpose described, said guide for the tongued flap gradually tapering to an end, and an over-

head guide arranged to press the tongue securely into interlocked relation in said slot.

9. In a machine for package closure, a series of moving cages, each adapted to receive and retain an erect carton, with a portion adjoining the base of each cage being slotted or cut away, a stationary support passing through said slotted or cut-away portion during a desired distance of travel of said cages, whereby said support provides a base on which the cartons may rest for 10 said desired distance of travel.

10. In a machine for package closure, a series of moving cages, each adapted to receive and retain an erect carton, with a portion adjoining one side of each cage being slotted or cut away, and an adjustable stationary guide passing 15 through said slotted or cut-away portion, whereby by adjusting the position of said guide, the cages are adapted to receive cartons of varying thickness, said guide thereby serving as one wall 20 of each cage, providing ready means of altering the dimension of each cage without the necessity of changing the cages themselves.

11. In a machine wherein erect cartons are introduced into a cage with the forward flap folded back, a cage, and a spring-latch on said cage to retain said flap in folded position, and means to subsequently release said latch.

12. In combination in a packaging machine, 30 conveying means having means thereon to receive and retain a lined carton open at both ends, means to close the liner, means to close the carton flaps over the liner, and means intercepting the path of the conveying means for providing a raised base in said carton receiving means, whereby the closed carton may be inverted, and thereafter supported with its other open end in position to be acted upon by closing means for the other end of the carton.

13. In combination in a packaging machine, 40 conveying means having means thereon to receive and retain a lined carton open at both ends, means to close the liner, means to close the carton flaps over the liner, and means intercepting the path of the conveying means for providing a raised base in said carton receiving means, whereby the closed carton may be inverted, and thereafter supported with its other open end in position to be acted upon by closing means for the other end of the carton, said carton receiving 45 means having cut away portions into which said intercepting means project.

14. In a machine for closing an erect carton having projecting liners and open flaps at one end at least, comprising means for closing the liners 55 at said end of the carton while the closing flaps are held out of the way, means for folding the liner out of the way of the carton flaps and retaining the liner so folded and means thereafter acting upon the closing flaps for closing them 60 and simultaneously inserting a tongue on one of the top flaps into a slot in the other top flap.

15. In a machine for closing an erect carton having projecting liners and open flaps at one end at least, comprising means for closing the liners 65 at said end of the carton while the closing flaps are held out of the way, and means thereafter acting upon the closing flaps for closing them and simultaneously inserting a tongue on one of the top flaps into a slot in the other top flap, means for reversing the carton to bring the closed end down, filling means for filling the carton after reversal thereof, and means thereafter acting upon the liner and the flaps at the then 70 75

upper end of the carton to close them, all of said mechanisms driven together in synchronism.

16. In a machine for closing an erect carton having projecting liners and open flaps at one end at least, comprising means for closing the liners at said end of the carton while the closing flaps are held out of the way, and means thereafter acting upon the closing flaps for closing them and simultaneously inserting a tongue on one of the top flaps into a slot in the other top flap, without disturbing the position of the liner.
- 10 one of the top flaps into a slot in the other top flap, means for reversing the carton to bring the closed end down, filling means for filling the carton after reversal thereof, and means thereafter acting upon the liner at the then upper end of the carton to close it, followed by means to close the flaps at the then upper end of the carton including means for simultaneously inserting a tongue on one upper flap into a slot in the other upper flap.
- 20 17. In a machine for closing an erect carton having projecting liners and open flaps at one end at least, comprising means for closing the

liners at said end of the carton while the closing flaps are held out of the way, means for folding the liner out of the way of the carton flaps and retaining the liner so folded and means thereafter acting upon the closing flaps for closing them and simultaneously inserting a tongue on one of the top flaps into a slot in the other top flap, without disturbing the position of the liner.

18. The method of interlocking a pair of opposite carton closure flaps one of which includes a projecting tongue and the other of which includes a slotted or weakened portion to receive the tongue which consists in imparting to the flaps simultaneously each an upward bend from its juncture line with the carton and a downward bend toward the middle of the carton while the carton is moving, thus bringing the edge of the tongue to the slotted portion and while the flaps are held together, releasing the bends, thus causing the tongue to enter the slot.
